**ASSEMBLY JIG FOR FACILITATING LOCK
TUMBLER CHANGE-OVER OPERATIONS**
William J. Kerr, Glenview, Ill., assignor to Chicago Lock
Company, Chicago, Ill., a corporation of Illinois
Filed June 26, 1964, Ser. No. 378,241
8 Claims. (Cl. 70—372)

The present invention relates to an assembly jig for facilitating lock tumbler change-over operations and has particular reference to such an assembly jig whereby the forward shaft tumbler pins of a lock assembly of the type that embodies an annular series of split pin tumblers may be removed from the lock assembly en masse and a new series of replacement shaft tumbler pins may then be installed in the lock assembly in order to effect a change in the lock combination.

There has long been on the market a class of lock assemblies which are commonly known as "Ace" locks and are manufactured by Chicago Lock Company of Chicago, Illinois. An "Ace" lock is principally characterized by the fact that the lock shaft projects completely through the fixed lock barrel and is provided with an enlarged head which is coaxial with the barrel, there being in the barrel an annular series of axially slidably barrel tumbler pins which cooperate with longitudinally aligned axially slidable shaft tumbler pins in the enlarged head in the usual manner of end-to-end cooperation between barrel and shaft tumbler pins. Invariably, an "Ace" type of lock is provided with a removable forwardly disposed cap which conceals the forward shaft tumbler pins, but which, when removed, exposes the front ends of these tumbler pins so that the pins may be pulled axially forwardly from their respective bores and interchanged or replaced by other shaft tumbler pins to change the combination of the lock assembly. After the interchange or substitution has been effected, the cap is replaced and the original key is discarded in favor of a new key which is designed to fit the new lock combination.

The assembly jig of the present invention has been designed specifically for use in connection with an axial pin tumbler lock of the aforementioned type and comprises two parts, namely, a coded package unit containing a supply of new or replacement shaft tumbler pins, and a combined pin extraction and pusher unit. The coded package unit is in the form of a generally cylindrical shell which is formed of molded plastic or other inexpensive disposable material and in which the new or replacement shaft tumbler pins are releasably held in the axial positions which they will assume when installed in the lock assembly and coded according to length to accommodate the selected new lock combination. The combined pin extraction and pusher unit is in the form of an effective double-ended cylindrical tool, one end of which carries a magnet to withdraw the exposed original shaft tumbler pins from the lock assembly after removal of the cap at the front of the assembly, and the other end of which carries a plurality of pusher pins for dislodging the new tumbler pins from the plastic shell of the coded package unit and pushing them endwise into the empty bores resulting from withdrawal of the original shaft tumbler pins by the magnet. Both the coded package unit and the combined pin extraction and pusher unit or tool are provided with various alignment means, useable first to secure proper alignment of the package unit with the front portion of the lock assembly in such a manner that registration of the new shaft tumbler pins with the proper shaft bores will be assured preparatory to pushing of said new shaft tumbler pins to their home positions, and secondly, to secure

2

proper alignment of the tool with the package unit in such a manner that pusher pin and shaft tumbler pin registry will be assured to the end that the new shaft tumbler pins may then be finally pushed axially to their home positions.

An assembly jig of this character will be found useful by a lock manufacturer's customer who, desiring to effect a change in the combinations of a number of "Ace" type lock assemblies, may obtain from the manufacturer the necessary number of coded package units with new and different annular sets of shaft tumbler pins therein, together with one of the pin extraction and insertion units or tools, and conveniently make the necessary change-over operations himself, discarding the empty shells of the package units as the change-over operations are completed.

The provision of an assembly jig for lock assembly changeover operations as briefly outlined above being among the principal objects of the invention, it is another object to provide such an assembly jig wherein the customer or other operator need not concern himself with specific shaft tumbler pin placement, the only duty incumbent upon him in making a change-over operation of a particular lock assembly being to order by code number a package unit containing a shaft tumbler pin combination differing from that to be replaced, together with the proper replacement key, after which the desired change-over operation may be put into effect without the operator even so much as touching any of the original shaft tumbler pins or the new or replacement shaft tumbler pins.

It is another object of the invention to provide such an assembly jig wherein the package unit containing the new or replacement shaft tumbler pins is so designed that the pins that are associated therewith are securely held within the unit against dislodgment, their coded positions being maintained at all times until the pins are ejected into a given lock assembly by means of the pusher part of the aforementioned combined pin extraction and pusher unit or tool. The unit may thus be subjected to rough handling as a mailable package without danger of internal shaft tumbler pin misplacement and consequent loss of coding.

Other objects and advantages of the invention, not at this time enumerated, will become readily apparent as the nature of the invention is better understood.

In the accompanying three sheets of drawings forming a part of this specification, one illustrative embodiment of the invention has been shown.

In these drawings:

FIG. 1 is a fragmentary exploded front perspective view of an axial pin tumbler lock assembly of the type that is capable of being serviced for change-over operations by the assembly jig of the present invention, such view showing the cap of the lock assembly in its removed position and illustrating the accessibility of the shaft tumbler pins for change-over from a first tumbler combination to a second tumbler combination;

FIG. 2 is an exploded perspective view similar to FIG. 1 but illustrating the initial withdrawal of the shaft tumbler pins from the bores in the enlarged head of the shaft of the lock assembly by way of the magnet part of the combined pin extraction and pusher unit or tool of the assembly jig constituting the present invention;

FIG. 3 is an exploded perspective view similar to FIGS. 1 and 2, but illustrating the manner in which the package unit containing the coded replacement shaft tumbler pin combination is juxtaposed with respect to the partially dismantled lock assembly directly following removal of the original shaft tumbler pins from their respective faces in the enlarged head of the shaft and also the manner in which the pusher part of the combined

extraction and pusher unit or tool is juxtaposed with respect to the package unit preparatory to simultaneous ejection of the new coded shaft tumbler pin combination from said package unit;

FIG. 4 is a sectional view taken substantially centrally and longitudinally through the lock assembly at the time the assembly jig is brought into play to effect insertion of the new shaft tumbler pins into the bores in the enlarged head of the shaft of the lock assembly;

FIG. 5 is an end view of the magnet part of the combiner pin extraction and pusher unit or tool of the present invention;

FIG. 6 is a sectional view taken substantially along the line 6—6 of FIG. 5;

FIG. 7 is an end view of the pin pusher part of the combined tumbler pin extraction and pusher unit or tool of the assembly jig;

FIG. 8 is a front end elevational view of the package unit which forms a part of the assembly jig and contains coded new or replacement shaft tumbler pin combination;

FIG. 9 is a rear end elevational view of the package unit of the assembly jig;

FIG. 10 is a sectional view taken substantially along the line 10—10 of FIG. 9 and showing one of the replacement shaft tumbler pins removed in order to illustrate the action of a certain O-ring that is employed in connection with the package unit of the assembly jig; and

FIG. 11 is an enlarged fragmentary sectional view taken on the line 11—11 of FIG. 10.

Referring now to the drawings in detail and in particular to FIG. 1, there is illustrated therein a lock assembly 10 which is of the axial pin tumbler type and is exemplary of a particular lock in which tumbler pin change-over operations may readily be accomplished by the use of the assembly jig of the present invention. The lock assembly 10 is of the type that is shown and described in my copending United States patent application Serial No. 336,795, filed on January 9, 1964, and entitled "Quick-Change Axial Pin Tumbler Lock Assembly." Only such details of the lock assembly 10 as are pertinent to the present invention have been illustrated in the drawings, but for a full understanding of the operation of the lock assembly, reference may be had to the aforesaid copending application. Briefly, the lock assembly 10 is designed for use on a vending machine cabinet door where managerial policy dictates that frequent changes in the split pin tumbler combination be made. As shown in FIG. 4, the lock assembly 10 includes a non-rotatable lock barrel 12 which is projected through an opening 14 in the cabinet door 16 and is held in position therein by a clamping nut 18 on the rear side of the door. A rotatable lock shaft 20 projects axially through the barrel 12 and carries at its rear end the usual radially extending locking cam 22 which is secured in place by a nut 24 on a rearwardly extending screw-threaded stem 26 on the rear end of the lock shaft 20. The lock shaft 20 is provided with an enlarged head 28 immediately forwardly of the barrel 12. The barrel 12 and the enlarged head 28 are provided with the usual split pin tumbler arrangement including barrel tumbler pins 30 and shaft tumbler pins 32. Such pins are arranged in two aligned annular series and are slidably disposed in respective bores 31 and 33 in the barrel 12 and the enlarged head 28. A circular protective washer 34 is provided forwardly of the cabinet door 16 and is suitably connected to the front end of the barrel 12; and an annular cap 36 (see FIG. 1) is adapted to seat within the shallow forwardly facing recess 38 that is formed by the washer 34. The cap 36 is provided with two oppositely disposed rearwardly extending hook portions 40 which latch behind arcuate shoulders 41 on the enlarged head 28 of the shaft 20 and normally prevent removal of the cap. When in position within the recess 38, the cap prevents access to the

shaft tumbler pins and also prevents such pins from being ejected from their respective bores 33 by the usual helical compression springs which are mounted on the rear ends of the bores 31 for the barrel tumbler pins 30. When the cap 36 is removed from the protective washer 34 of the lock assembly, the shaft tumbler pins 32 are exposed as shown in FIG. 1 and they may then be withdrawn forwardly from the enlarged head 28 of the lock shaft. Said enlarged head 28 is provided with a forwardly extending pilot stem or post 42 which is designed for reception thereover of a socket 44 in the front or tumbler-engaging end of a lock manipulating key, such, for example, as either of the keys 46 and 48 that are shown in FIG. 1. Either key is adapted to be projected through a central opening 50 in the cap 36 and, when so projected, shoulders 52 on the front end of the key cooperate with the front ends of the shaft tumbler pins 32 in the usual manner of key and tumbler cooperation.

The arrangement of parts thus far described constitutes no part of the present invention and represents merely an exemplary form of lock assembly having shaft tumbler pins which are capable of being exposed by removal of the cap at the front end of the lock assembly and are adapted to be replaced by means of the assembly jig which constitutes the present invention and will now be described in detail.

As shown in FIGS. 2 and 3 of the drawings, the assembly jig of the present invention consists of two independent parts or units, namely, a coded package unit 60 containing and including a series of replacement shaft tumbler pins 32A, and a combined tumbler pin extraction and pusher unit or tool 62. Briefly, the combined extraction and pusher unit 62 is in the form of a double-ended tool, one end of which carries a thin flat annular magnet 64 for attracting and withdrawing the shaft tumbler pins 32 from the bores 33, and the other end of which carries an annular series of pusher pins 66 for pushing the new or replacement shaft tumbler pins 32A out of the package unit 60 and installing them in the bores 33 which are left empty by withdrawal of the original shaft tumbler pins 32.

As best seen in FIG. 3 and FIGS. 8 to 11, inclusive, the package unit 60 comprises a shell 70 which is of cylindrical cup-shaped design and embodies a generally cylindrical side wall 72 and a relatively thick annular rear end wall 74. Preferably, the shell is formed of molded plastic material to the end that it may be discarded after it has served its intended purpose. The upper region of the side wall 72 is upwardly offset as at 76 in order to form or establish an elongated, inwardly facing, longitudinally extending, spline-receiving channel 78 for cooperation with a spline 80 which is associated with and forms a part of the unit or tool 62 as will be described presently. The rear end wall 74 of the shell 70 is formed with a central opening 82 (see FIG. 10) therein and the upper portion of the rim of this opening is provided with an inwardly extending lug 84 which is designed for cooperation with a horizontal groove 86 in the key-centering pilot stem or post 42 at the front end of the lock shaft 20 of the lock assembly 10.

The annular rear end wall 74 of the shell 70 is provided therein with an annular series of axially extending bores 88, each bore having disposed therein one of the replacement shaft tumbler pins 32A. The inner end of the inner peripheral portion of the annular rear end wall 74 is formed or provided with a narrow, integral, reentrant or inwardly extending flange 90 around which there is stretched a resilient rubber O-ring 92. The latter is disposed for the most part in an annular groove which is defined by the outer periphery of the flange 90 and the adjacent portion of the shell side wall 76. The bores 88 are aligned with, and pass axially through, the flange 90. The outer portions of the inner ends of the bores 88 intersect the outer periphery of the flange 90 and, hence, open onto the groove 94 as shown in FIGS. 9 and 11. The

O-ring thus normally has a limited portion of its inner periphery projecting into the outer portion of the inner end of each bore 88 as shown at the top right-hand region of FIG. 10 where one of the shaft pins 32A has been removed in the interest of clarity. However, with the shaft pins 32A in position within the bores 88, the O-ring 92 is displaced by such pins as shown at the bottom right-hand region of FIG. 10, and also in FIG. 11, so that the O-ring serves in the manner of a garter spring frictionally to retain the various shaft tumbler pins 32A in position within their respective bores 88.

As shown in FIGS. 3 to 7, inclusive, the combined tumbler pin extraction and pusher unit or tool 62 (which, in the interest of brevity, will hereinafter be referred to simply as the tool) is in the form of a thick-walled cylindrical body 100 which has at one end thereof an enlarged head portion 102 and which contains the previously-mentioned thin flat annular magnet 64. This magnet is of the barium ferrite type. It is commonly referred to as a "ceramic" magnet and is fixedly held in place by way of a so-called press fit. An annular series of circumferentially spaced bores 106 (see FIG. 6) extends in an axial direction through the wall of the body 100. Such bores correspond in number to, and serve as retainers for, the pusher pins 66 and are restricted as at 108 at the ends thereof that intersect the end of the body that is remote from or opposite to the enlarged head portions 102. The major portions of the pusher pins 66 project outwardly of the bores 106 through the restricted ends thereof. Helical compression springs 110 are disposed in a lengthwise manner in the bores 106 and serve to urge the pusher pins outwards. Certain ends of the springs abut against the inner end surface of the magnet 64 and the other ends of the springs abut against enlarged heads on the inner ends of the pusher pins. The bores 106 and the pusher pins 66 correspond in number and spacing to the number and spacing of the bores 88 and the shaft tumbler pins 32A, the latter, in turn, corresponding in number and spacing to the number and spacing of the pin-receiving bores 33 in the enlarged head 28 of the lock shaft 20 of the lock assembly 10. The previously-mentioned spline 80 is formed on the outer surface of the cylindrical body 100 of the tool 62. It extends lengthwise of said body and is shaped to fit in the channel 78 when the small portion of the tool is inserted into the cylindrical side wall 72 of the shell 70 of the package unit 60 in connection with use of the tool to eject the shaft tumbler pins 32A into the bores 33.

While the shell 70 of the package unit 60 may be formed of any suitable material, as heretofore mentioned, it is preferably formed of transparent "Lucite" in order that the shaft tumbler pins 32A in the bores may be visible through the shell. The shell 70 is intended to be disposable in that it may be discarded after the new or replacement shaft tumbler pins 32A have been ejected therefrom and installed in the lock assembly 10, but under certain circumstances, it may be found expedient to retain the shell and install the original shaft tumbler pins 32 therein for future use in the event that it is desired to restore these original pins in the lock assembly 10 or to install them in some other similar lock assembly.

The sequential steps performed in effecting a change-over operation by means of the present jig assembly have been shown in FIGS. 1 to 4, inclusive. In FIG. 1, the lock assembly 10 is shown with the cap 36 removed in order to expose the forward ends of the shaft tumbler pins 32, the tumbler shaft pins being coded in conformity with the key 46 which has been labelled "Combination A." The key 48 which has been labelled "Combination B" is intended to accommodate the lock assembly 10 after the replacement shaft tumbler pins 32A of the package unit 60 of FIG. 3 have been installed in the lock assembly.

After initial removal of the cap 36 as shown in FIG. 1, the magnet-containing front end of the tool 62 is applied to the exposed or protruding ends of the shaft tumbler

pins 32 and the latter are transferred by magnetic attraction from the lock assembly endwise to the magnet 64 as shown in FIG. 2. The pins may be removed from the magnet and discarded or they may be preserved for future use if desired.

With the bores 33 in the enlarged head 28 of the lock shaft 20 now empty by reason of the withdrawal of the shaft tumbler pins 32, the package unit 60 is positioned as shown in FIG. 3 and the pilot post 42 of the lock assembly 10 is caused to enter the central opening 82 in the end wall 74 of the shell 70, the groove 86 and the lug 84 assuring proper registration of the replacement shaft tumbler pins 32A with the bores 33. The shell 70 is pushed rearwardly so that it enters the recess 38 in the protective washer 34 and, thereafter, the tool 62 is turned end-for-end so that the pusher pin-containing end thereof registers with the front end of the shell 70 of the package unit 60. Thereafter, the tool 62 is pushed rearwardly and telescopically into the shell 70. The spline 80 on the tool 62 and the spline-receiving channel 78 of the shell 70 assure register of the various pusher pins 66 with the adjacent ends of the replacement shaft tumbler pins 32A in the shell 70.

As shown in FIG. 4, the final step in the installation of the replacement shaft tumbler pins 32A in the lock assembly 10 resides in forcibly pushing the tool 62 rearwardly so that the pusher pins 66 will displace the shaft tumbler pins 32A and force them into the bores 33 in the enlarged head 28 of the lock shaft 20. Movement of all of the new or replacement shaft tumbler pins 32A to their home position in the lock assembly 10 is assured by reason of the springs 110 which allow the pusher pins to yield when the shaft tumbler pins 32A have become bottomed in their respective bores 33.

Upon withdrawal of the tool 62 and the package unit 60 from the lock assembly, the pins 32A remain in place and the cap 36 (FIG. 1) may then be again installed as part of the lock assembly, and the change-over operation is complete.

The invention is not to be limited to the exact arrangement of parts shown in the accompanying drawings or described in this specification as various changes in the details of construction may be resorted to without departing from the spirit or scope of the invention. Therefore, only insofar as the invention has particularly been pointed out in the accompanying claims is the same to be limited.

Having thus described the invention what I claim as new and desire to secure by Letters Patent is:

1. The combination for use with an axial pin tumbler lock assembly having a lock shaft provided with a circular forward end face presenting a series of forwardly opening bores designed for reception endwise therein of a series of replacement tumbler pins, of a two-part assembly jig for facilitating the introduction of such replacement pins into said bores, said assembly jig including a first part in the form of a generally cylindrical cup-shaped shell having a relatively thick rear end wall provided with an annular series of circumferentially spaced axially extending open-ended bores therein conforming in number and disposition to the number and disposition of said bores in said end face, replacement tumbler pins slidably disposed in the bores in said end wall, means yieldingly restraining the tumbler pins against free sliding movement within their respective bores, and a second part in the form of a generally cylindrical pusher tool receivable telescopically and endwise in said shell, said pusher tool having a circular rear end face from which there projects rearwardly a series of pusher pins corresponding in number and disposition to the number and disposition of the bores in said end wall, said pusher pins being adapted for entry into the bores in said end wall so as to engage the tumbler pins within said latter bores and displace the same simultaneously and force them into the forwardly opening bores in the end face of the lock shaft.

2. The combination set forth in claim 1 and including, additionally, interengaging pilot means on said pusher tool and shell for maintaining the pusher tool and lock shaft in axial alignment during entry of the pusher pins into said bores.

3. The combination set forth in claim 1 and including, additionally, interengaging pilot means on said pusher tool and shell for maintaining the pusher tool and shell in axial alignment during entry of the pusher pins into said bores, said pilot means including a spline connection for preventing relative turning movement of the pusher tool and shell.

4. The combination set forth in claim 1 and wherein, said lock shaft is provided with a forwardly extending pilot stem which projects forwardly from said circular forward end face centrally of the latter, said shell being provided with an axially and centrally disposed bore in the rear end wall thereof designed for telescopic reception over said pilot stem.

5. The combination set forth in claim 1 and wherein said lock shaft is provided with a forwardly extending pilot stem which projects forwardly from said circular forward end face centrally of the latter, said shell being provided with an axially and centrally disposed bore in the rear end wall thereof designed for telescopic reception over said pilot stem, said stem and bore being provided with an interengaging spline connection to prevent relative turning movement of the lock shaft and shell.

6. The combination set forth in claim 5 and including, additionally, interengaging pilot means on said pusher tool and shell for maintaining the pusher tool and shell in axial alignment during entry of the pusher pins into said bores.

7. The combination set forth in claim 5 and wherein said shell is formed with an internal spline groove therein, and wherein said pusher tool is provided with an external spline rib designed for interlocking engagement with

said spline groove to prevent relative turning movement of the pusher tool and shell.

8. The combination for use with an axial pin tumbler lock assembly having a lock shaft provided with a circular forward end face presenting a series of forwardly opening bores designed for reception endwise therein of a series of replacement tumbler pins, of a two-part assembly jig for facilitating the introduction of such replacement pins into said bores, said assembly jig including a first part in the form of a generally cylindrical cup-shaped shell having a relatively thick rear end wall provided with an annular series of circumferentially spaced axially extending open-ended bores therein conforming in number and disposition to the number and disposition of said bores in said end face, replacement tumbler pins slidably disposed in the bores in said end wall, means yieldingly restraining the tumbler pins against free sliding movement within their respective bores, and a second part in the form of a generally cylindrical pusher tool receivable telescopically and endwise in said shell, said pusher tool having a circular rear end face provided with a series of sockets therein corresponding in number and disposition to the number and disposition of the bores in said end wall, a pusher pin slidably disposed in each of said sockets and projecting rearwardly beyond and outwardly of said rear end face of the pusher tool, and springs disposed in said sockets and yieldingly urging said pusher pins to their projected positions.
